UNITED STATES PATENT OFFICE.

WILLIAM E. FITCH, OF LOUISVILLE, KENTUCKY.

DESIGN FOR A FIREPLACE-FRONT.

SPECIFICATION forming part of **Design No. 21,444**, dated April 5, 1892.

Application filed February 24, 1892. Serial No. 422,692. Term of patent 3½ years.

To all whom it may concern:

Be it known that I, WILLIAM E. FITCH, a citizen of the United States, residing at Louisville, in the county of Jefferson and State of Kentucky, have invented a certain new and useful Design for Fireplace-Fronts, of which the following is a full, clear, and exact description.

This design relates to a fireplace-front having what is known in the trade as a "summer front."

The leading feature of the design is a representation of a berry-bearing spray and a bent ribbon spreading out on either side from a rosette or center of curvilinear raised portions. The background may be roughened or stippled.

In the accompanying drawing I have shown my design on only half of the front, it being

understood that it is duplicated on the other half.

The letter *a* designates what I term the berry-bearing spray, *b* the folded or bent ribbon, and *c* the rosette or center.

d is the roughened or stippled background.

The general appearance of the design is that of interior decorations of olden times.

What I claim is—

The design for a fireplace-front, substantially as shown and described.

In testimony whereof I have hereunto set my hand this 20th day of February, A. D. 1892.

WILLIAM E. FITCH.
